Inventor,

Thomas Tansley Jr.

Thomas Tansley Jr.

Attorney.

UNITED STATES PATENT OFFICE.

THOMAS TANSLEY, JR., OF BALTIMORE, MARYLAND, ASSIGNOR TO DICKEY,
TANSLEY & CO., OF SAME PLACE.

GAS-METER.

SPECIFICATION forming part of Letters Patent No. 239,282, dated March 22, 1881.

Application filed January 24, 1881. (Model.)

To all whom it may concern:

Be it known that I, THOMAS TANSLEY, Jr., of Baltimore city, State of Maryland, have invented certain new and useful Improvements 5 in Gas-Meters; and I hereby declare the same to be fully, clearly, and exactly described, as follows:

My invention has reference to apparatus for determining the quantity of gas delivered 10 through pipes, and relates, particularly, to means for preventing fraudulent tampering with the meter.

In the so-called "dry" or "diaphragm" meters the registering mechanism is operated by 15 a system of cranks, which are moved by the diaphragm, which latter operates the valves that regulate the delivery of gas to the pipes leading to the burners. It is patent that upon lifting the valves by any means an escape for 20 the gas directly from the inlet to the outlet pipes is afforded, and the device ceases to register. Parties possessing more ingenuity than conscience, perceiving this fact, have devised means for lifting the valves, which means has 25 generally consisted of a piece of wire inserted through the outlet-pipe and channel leading thereto from the valve, and made to raise the latter from its seat. To defeat this I have devised the form of apparatus shown in the accompanying drawings, in which—

Figure 1 is a plan view of the valve-chamber end of an ordinary dry-meter; Fig. 2, a central sectional view of the side of the meter and supply-pipe leading to the burners. Fig. 35 3 is a plan view of the hood or baffle plate; Fig. 4, a sectional view of a tube embodying the same principle, ready for attachment to meters in common use; and Fig. 5 is a similar view of a modified form of device for attaining 40 the same end.

A is the meter, having supply-pipe B, inlet-pipe C, and registering mechanism D, operated by rods $a a' a'' a'''$, shaft c , wheel b , and shaft b' .

45 F is the valve-chamber, having slide-valves E, operated by a crank on the shaft c ; and e is the gas-orifice leading from the pipe C. I shall not describe these parts nor their operation minutely, as they are of the usual construction and form no part of my invention.

Experience has shown that by introducing a bent wire through the pipe B and duct f the valves E may be lifted, and to prevent this, in the case of new meters, I strike up a hood or baffle-plate, G, (see Fig. 3,) from sheet-metal, 55 leaving flanges i' and wings i , which latter are bent at right angles to the front portion. The hood is soldered to the side of the meter over the orifice g leading to the pipe B, and is covered by the latter, as shown in Fig. 2. 60

In applying the invention to meters in use I provide a tube, B', of a size to fit in the pipe B, and furnished on its interior with zigzag plates G'. I apply solder and flux to its exterior and drop it in the pipe B, and then melt 65 the solder by means of a hot iron applied to the surface of the pipe B, securing the tube in place. In lieu of either expedient I solder inside the duct f a wire-gauze partition, H, the ends of which opposite the parts of the duct 70 are covered by plates h . The end f' is opposite the opening g , and the effect of the gauze and plates h is to prevent the passage of a wire into the duct, while allowing of the free passage of gas. 75

It will be understood that the insertion of wire into the duct to raise the valve is impossible with either form of device described, and the same may be applied to meters, either in the course of manufacture or already in use, at 80 trifling cost.

What I claim is—

1. In combination with the gas-duct of a meter, a baffle-plate secured within the said duct and adapted, as described, to defeat the insertion 85 of a wire or other substance into the same and in contact with the valve, while not obstructing the flow of gas, as set forth.

2. In combination with the gas-duct of a meter, an inclined plate secured in contact with 90 the walls of the duct at one side, and having its unattached edge projecting partly across the duct, as set forth.

THOS. TANSLEY, JR.
